UNITED STATES PATENT OFFICE.

EVERETT B. CUSHMAN, OF LANSING, MICHIGAN, ASSIGNOR TO BEAN SPRAY PUMP CO., OF SAN JOSE, CALIFORNIA, A CORPORATION OF CALIFORNIA.

POWER-UNIT ASSEMBLY.

Application filed August 11, 1923. Serial No. 656,952.

To all whom it may concern:

Be it known that I, EVERETT B. CUSHMAN, a citizen of the United States, residing at Lansing, in the county of Ingham 5 and State of Michigan, have invented certain new and useful Improvements in Power-Unit Assemblies, of which the following is a specification.

This invention relates to internal combustion engines and especially an engine, radiator, water pump, and fly wheel assembly. It is the object of the invention to provide an assembly compactly arranged. The pump and fly wheel are mounted directly on the 15 crank shaft and the radiator is concentric to the crank shaft. This arrangement protects the radiator, saves space, eliminates an extra pump shaft or the lengthening of the magneto shaft, and eliminates unnecessary 20 parts and accessories at the side of the engine.

Another invention involved in this application and which is ancillary to the arrangement of the parts above referred to, is the 25 pump construction itself. This pump is provided with a pair of packing glands and a runner, so arranged that the adjustment of one packing gland at the outside serves to adjust both packing rings. This makes 30 possible the use of a pump concealed between the fly wheel and the radiator. When necessary to reach the pump one has simply to remove the fly wheel which exposes the 35 entire side of the pump so that it can then be quickly disengaged from the radiator headers. These and other features will be explained more in detail hereinafter.

In the drawings:

Fig. 1 is a side elevation of a single cylinder engine equipped with my improved assembly.

Fig. 2 is an elevation of the centrifugal pump.

Fig. 3 is a cross section of the same taken 45 on the line 3—3 of Fig. 2.

Fig. 4 is a fragmentary elevation of the fly wheel which is broken away to show a front elevation of the radiator and pump.

The cylinder block is designated *a* and 50 here embraces a single cylinder engine, but obviously the number of cylinders is immaterial. The other accessories such as the carburetor *b*, spark plug *c*, oil cup *d*, magneto *e*, intake manifold *f*, and exhaust pipe *g*, are all apparent from the drawings. The

extension of the crank case designated *h* is bolted to the angle-section ring *i* which forms the center of the cooling radiator *j*. The water is drawn through the hose connection *k* from the engine water jacket directly through the top header *m* of the radiator, through the hose connection *n* and suitable fittings, to the centrifugal pump *o*. This pump comprises a pump casing *p*, a cover *q*, bolted to the casings, a runner or rotor *r*, provided with a long integral hub *s*, keyed to the crank shaft *t*. The pump casing *p* is a casting provided with an inwardly projecting sleeve *u* which forms a bearing for the hub of the rotor. The outer 60 end of the sleeve projects outwardly from the body of the casing forming an abutment *v* having a tapered or conical seat *w*, which in connection with the parts to be described, acts as a packing gland. The cover plate *q* is provided with an inwardly projecting sleeve *x* screw threaded to take the packing gland *y* that screws into it. The hub of the runner is thickened near the center to provide a journal for the runner in the bearings *x* and *u* and for the further purpose of transmitting the pressure applied by the gland *y* to the packing *z*. This pressure is transmitted by the center of the hub from the packing *z* to the packing *1* on the opposite side of the pump. This packing *1*, being forced against the tapered seat *w* that forms the opposite gland, serves to crowd the packing tightly against the hub of the runner and the bearings, thereby tightening 65 the packing on both sides of the pump simultaneously.

This is a very useful and necessary feature in connection with the location of the pump on the crank shaft, and between the fly 70 wheel and the motor, for with the one side of the pump directly up against the motor it will be seen that it would be impossible to have access to this side of the pump to adjust the packing on this side of the pump.

The packing gland *y* is provided with an integral arm *2* which may be engaged by a tool inserted through one of the apertures *3* in the web of the fly wheel. When the tool has been butted up against this arm, the fly 75 wheel and tool may be turned in either direction to tighten or loosen the gland provided the set screw *4* be loosened. This may be loosened by a screw driver inserted through the air openings *5* in the periphery 80

of the fly wheel. It will be noticed the fly wheel is an integral casting provided with vanes 6 so that air is drawn in through the periphery of the fly wheel and discharged against the face of the rotor and the water pump.

The arrangement that I have described makes a very neat, compact, and convenient assembly for a stationary engine. It will be noticed that the fly wheel, radiator and pump, are all concentric to the crank shaft. The radiator is bolted directly to the crank case by means of its central ring. The pump is supported on the crank shaft, and by the connections with the radiator. The fly wheel, of course, is supported directly on the crank shaft. By removing the nut 6' the fly wheel may be taken off the crank shaft and the face of the pump is exposed directly at the end of the engine so that the pump may be easy of access and the radiator is also exposed and may be easily removed after first removing the pump.

I have here shown the pump as a centrifugal pump, but obviously it may be any other form of rotary pump. In this centrifugal pump the water is drawn directly through the upper head of the rotor, through the hose connection *n*, into the central annular chamber 7 of the pump. It is then drawn into the central chamber 8 of the runner or rotor, and thrown out the periphery of the rotor through the passages 9 into the chamber 10. It is then forced through the connections 11 into the bottom header 12 of the radiator, and thence led through the radiator to the top header thence it returns to the engine through the tubular connections 13.

40 What I claim is:

1. The combination of a water jacketed engine provided with a crank shaft extended at one end, a radiator provided with upper and lower headers and concentric with the extended crank shaft, a water pump having a rotating member mounted on the crank shaft, a conduit leading from the water jacket through the top of the radiator to the pump, a conduit leading from the pump to the lower header of the radiator, and a conduit leading from the upper header of the radiator to the water jacket.

2. The combination of a water jacketed engine provided with a crank shaft extending outwardly beyond the engine bearing, a radiator concentric with the crank shaft, a pump provided with packing and having a rotating member mounted on such extended crank shaft, and means operable at one side of the pump for simultaneously adjusting the packing at both sides of the pump.

3. The combination of a water jacketed engine provided with a crank shaft extending outwardly at one end, a radiator mounted concentrically to such extended

crank shaft, a pump provided with packing and having a rotating member mounted on such extended crank shaft, a fly wheel mounted on and near the end of the extended crank shaft, and means accessible from the outside of the fly wheel for adjusting the packing in the pump.

4. The combination of a water jacketed engine having at one side an outwardly extended crank shaft, a pump provided with packing and mounted concentric to the outwardly extended crank shaft and having a rotating member mounted thereon, and a gland on the outside of the pump for simultaneously adjusting the packing at both sides of the pump.

5. The combination of a water jacketed engine provided at one end with an outwardly extending crank shaft, a water pump mounted concentric thereto and having a rotating member mounted on said crank shaft, said pump provided with an abutment at one side having a tapered seat and a packing engaging said seat, and a gland and packing at the other side of the pump adjustable to shift the rotor and adjust the packing at the opposite side of the pump by means of the said tapered seat and the shifting of the rotor.

6. The combination of a water jacketed engine provided at one end with an outwardly extending crank shaft, a radiator fastened to the engine and concentric with the crank shaft, a centrifugal pump provided with packing and with suitable connections through the radiator to the water jacketed engine, the said pump being provided with a runner mounted directly on the crank shaft, a fly wheel near the end of the extended portion of the crank shaft, and means accessible through the fly wheel to adjust the packing at both sides of the pump.

7. The combination of a water jacketed engine provided at one end with an outwardly extending crank shaft, a radiator mounted concentrically to the crank shaft, a rotary pump packed at both sides and concentric to the crank shaft and provided with a runner mounted directly on the crank shaft, connections from the pump through the radiator to the water jacketed engine, a fly wheel mounted near the end of the crank shaft, and means accessible through the fly wheel for shifting the runner longitudinally of the shaft to adjust the packing on both sides of the pump.

8. The combination of a water jacketed engine provided at one end with an outwardly projecting crank shaft, a pump provided with packing at both sides and mounted concentrically to the crank shaft, the said pump provided with a tapered abutment at one side, a runner mounted directly on the crank shaft, and a packing

gland adjustable from the outside of the pump for shifting the runner longitudinally of the crank shaft to simultaneously adjust the packing on both sides of the pump in connection with the tapered abutment.

9. The combination of a water jacketed engine provided at one end with an outwardly projecting crank shaft, a water pump having a casing mounted concentrically to the crank shaft, the said pump being provided with a runner mounted directly on the crank shaft and packing at both sides thereof, the said runner having a hub with a thickened portion at the center to form an abutment, and the said pump casing provided at one side with an abutment having a tapered seat, and a packing gland on the outside of the pump in the form of a nut with a tapered inner end for engaging the packing at one side and for simultaneously adjusting the packing at the opposite side of the pump through the shifting of the runner longitudinally of the crank shaft.

10. The combination of a water jacketed engine provided at one end with an outwardly extending crank shaft, a radiator, a pump mounted concentrically with the outwardly extending crank shaft, and having packing at both sides, said pump having a runner mounted directly on the crank shaft, a fly wheel mounted on the end of the crank shaft and having an aperture through its web and a packing gland accessible through said aperture for simultaneously adjust the packing on both sides of the pump.

11. The combination of a water jacketed engine provided at one end with an out-

wardly extending crank shaft, a radiator, a pump provided with packing on both sides mounted concentrically to the outwardly extended crank shaft, suitable water connections between the pump, radiator and water jacket of the engine, a gland on the outside of the pump, a fly wheel mounted near the end of the crank shaft and having an aperture to give access to the said gland, the turning of which serves to adjust the packing on both sides of the pump simultaneously.

12. The combination of a water jacketed engine provided at one end with an outwardly extended crank shaft, a radiator supported around the shaft, a water pump provided with suitable connections with the radiator and the water jacket of the engine and having a rotating member mounted on the crank shaft, and a fly wheel near the center of which the pump is located, said fly wheel being supported on the crank shaft outside the radiator and pump, and the pump being located between the fly wheel and the radiator.

13. The combination of a water jacketed engine provided at one end with an outwardly extending crank shaft, a pump having a rotating portion secured on said extension of the crank shaft and a fly wheel secured on the end of the crank shaft and having a portion of its center cut away to permit the location of the pump within the fly wheel.

In testimony whereof I affix my signature.

EVERETT B. CUSHMAN.
